UNITED STATES PATENT OFFICE.

LEE F. HAMME, JR., OF OXFORD, NORTH CAROLINA.

BALL RACK FOR POOL TABLES.

Application filed January 2, 1925. Serial No. 210.

To all whom it may concern:

Be it known that I, LEE F. HAMME, Jr., a citizen of the United States, residing at Oxford, in the county of Granville and 5 State of North Carolina, have invented a new and useful Ball Rack for Pool Tables, of which the following is a specification.

This invention relates to a rack for use in placing balls on a pool table. Heretofore 10 it has been the practice to use a triangular frame for this purpose. This frame has been a separate piece which is easily misplaced and broken and requires more or less guess work in the proper placing of the 15 balls.

It is an object of the present invention to provide a ball rack which is built into the table and will always accurately position the balls, this rack being of such a type 20 that it will disappear after the balls have been racked and will at no time interfere with proper playing.

With the foregoing and other objects in view which will appear as the description 25 proceeds, the invention resides in the combination and arrangement of parts and in the details of construction hereinafter described and claimed, it being understood that changes in the precise embodiment of 30 the invention herein disclosed may be made within the scope of what is claimed without departing from the spirit of the invention.

In the accompanying drawings the preferred form of the invention has been 35 shown.

In said drawings

Figure 1 is a plan view of a portion of a table having the present improvements 40 combined therewith, the position of the rack under the top of the table being indicated by dotted lines.

Fig. 2 is a section on line 2-2, Fig. 1.

Fig. 3 is a section through a portion of 45 the table on line 3-3, Fig. 2.

Referring to the figures by characters of reference 1 designates a pool table which is of the ordinary construction except a recess 2 is formed in the table directly under 50 the point where the balls are to be racked, this recess being closed at the top by the usual slate 3 or other top structure of the table on which the felt covering 4 is placed.

In this recess is slidably mounted a triangular head 5 from which depends a stem 6

which projects through an opening 7 in the bottom of the table. A pitman 8 connects the lower portion of the stem to a crank arm 9 provided at one end of a shaft 10. This shaft is journaled in suitable bearing 60 11 and projects beyond one wall of the table where it is provided with a crank handle 12 or the like whereby the shaft can be rotated readily. The parts are so positioned that when the crank arm 9 is moved upwardly slightly past its dead center, it will bring the link 8 against a suitable stop 13 such as shown for example in Fig. 3.

Pins 14 are secured to the head 5 and are 70 slidable within openings 15 in the top of the table and if desired, these pins may be provided at their upper ends with coverings 16 of felt adapted, when the pins are in their lowermost positions, to fill the openings in the felt cover 4 which receive the pins when 75 raised.

The pins are so disposed that, when projected above the table top, they will define a space into which the balls can be placed. The pins are located in groups 17 at each 80 apex of the triangle defined thereby and additional pins are located between these groups 17 as shown at 18 in Fig. 1.

Under normal conditions the head 5 rests upon the bottom of the recess 2 and the 85 felt coverings of the ends of the pins 14 lie flush with the felt covering 4. Thus the table can be used as ordinarily without interference by the pins. When it is desired to rack the balls before beginning a game, 90 the crank handle 12 is shifted in one direction so as to cause the arm 9 to pull upwardly on pitman 8 and stem 6. Thus the head 5 will be elevated and the pins pushed upwardly to the position shown in Figs. 95 2 and 3. The balls can then be placed in the space surrounded by these pins and will quickly assume their proper relations to each other so as to form a compact triangular group. Immediately thereafter the pins can be retracted by moving the head 100 5 downwardly whereupon the table will be in condition for playing. It will be noted that when the pins are elevated and the link or pitman 8 is past its dead center and against stop 13, the parts will be held elevated until shaft 10 is positively rotated to lower them.

Obviously various means can be used for controlling the actuation to shaft 10. These 110

means can be in the form of check controlled apparatus and as the same constitutes no part of the present invention, no attempt has been made to disclose it in the 5 present case.

What is claimed is:—

1. The combination with a pool table, of a ball rack normally concealed under the top surface of the table, and means for elevating the rack to active position, said rack being disposed at all times inwardly from the edges of the table.

2. The combination with a pool table, of a rack normally concealed under the playing 15 surface of the table and means for actuating the rack to project ball engaging portions above the playing surface, said rack being disposed at all times inwardly from the edges of the table.

20 3. The combination with a pool table, of a plurality of pins slidable in the table and having their upper ends normally flush with the playing surface of the table, and means for projecting the pins upwardly above said surfaces for use as a ball rack.

30 4. The combination with a pool table, of pins slidably mounted therein and having their upper ends normally flush with the playing surface of the table, and means for simultaneously moving the pins upwardly relative to said surface to form a ball rack.

35 5. The combination with a pool table, of a structure concealed therein and mounted for sliding movement, a plurality of pins projecting from said structure and normally flush with the playing surface of the table, and means for shifting said structure relative to the table to simultaneously project the upper ends of the pins to positions above

the playing surface, thereby to constitute a 40 ball rack.

6. The combination with a pool table having a recess below the playing surface thereof, of a structure mounted for reciprocation within said recess, ball racking means carried by said structure and shiftable to position above the playing surface of the table, and means for elevating and holding said ball racking means in ball retaining position.

50 7. The combination with a pool table having a recess below the playing surface thereof, of a structure mounted for reciprocation within the recess, pins extending from said structure and slidable in the top 55 of the table, said pins being normally flush with the table top, means for shifting said structure to project the pins above the table top, and means for holding the pins in projected positions.

8. The combination with a pool table having a recess therein, of a head mounted for up and down movement therein, pins projecting from the head and slidable in the top 65 of the table, said pins being normally flush with the playing surface of the table, a stem depending from the head, an actuating shaft, means provided by the shaft for elevating the head to shift the pins above the playing 70 surface, and means for holding the head and pins in elevated position.

In testimony that I claim the foregoing as my own, I have hereto affixed my signature in the presence of two witnesses.

LEEE F. HAMME, JR.
